W. J. SMITH.

DETACHABLE BUTTON,

APPLICATION FILED FEB. 28, 1916.

1,193,936.

Patented Aug. 8, 1916.

FIG. I

UNITED STATES PATENT OFFICE.

WILLIAM J. SMITH, OF WATERBURY, CONNECTICUT.

DETACHABLE BUTTON.

1,193,936.

Specification of Letters Patent. Patented Aug. 8, 1916.

Application filed February 28, 1916. Serial No. 81,015.

To all whom it may concern:

Be it known that I, WILLIAM J. SMITH, a citizen of the United States, residing at Waterbury, in the county of New Haven, 5 State of Connecticut, have invented certain new and useful Improvements in Detachable Buttons; and I do hereby declare the following to be a full, clear, and exact description of the invention, such as will 10 enable others skilled in the art to which it appertains to make and use the same.

This invention relates to improvements in separable fasteners and is directed more particularly to a garment button embodying 15 separable elements whereby it may be readily attached to or detached from a garment.

An object of the invention resides in the provision of a fastener of this character in 20 which means are provided for the detachable connection of the elements, novel provision being made for releasing said means without distorting the same and detracting from the life of the button.

25 With the above and other objects of similar nature in view, the invention consists in the construction, combination, and arrangement of parts, set forth in and falling within in the scope of the appended claim.

30 In the drawing:—Figure 1 is a plan view of my improved button, the head being partially broken away. Fig. 2 is a central sectional view therethrough, and Fig. 3 is a detail sectional view taken on the line 35 3—3 of Fig. 1.

Referring now more particularly to the drawing, my improved fastener is shown as comprising a shell or head portion 10 consisting of a top member 11 and a bottom 40 member 12, said members having their marginal edges oppositely directed and crimped together as at 13 whereby a space 14 will be provided between the members. The bottom member 12 is further formed with a 45 central opening 15, the surrounding wall of which is directed laterally at 16 and provides a suitable bearing for receiving the shank portion of the button back.

The back member of the button is shown 50 at 17 and has rising centrally therefrom a shank 18, the latter terminating at its free end in a conical head 19 and being circumferentially reduced as at 20 adjacent said head.

55 The detachable connection for the members 10 and 17 of the button is illustrated

generally at 21 and is disposed and housed within the space 14 between the top and bottom members 11 and 12 respectively. This connection 21 consists preferably of a single 60 length of spring wire intermediately bent in circular form to fit singly within the inner circumference of the shell and has its end portions 22 extended inwardly of the circle in divergent relation so as to pass beyond 65 and normally intersect the opening 15 in the member 12. Thus to detachably connect the button members, the shank 18 of the back is inserted within the bearing 16 and through the opening 15 in the member 12, 70 the inclined surface of the conical head 19 engaging and spreading the ends 22 of the wire 21, and then passing beyond said ends while the latter spring into the reduced portion 20 of the shank and thereby prevent its 75 withdrawal. It will be noted that the top member 11 of the shell has its central portion pressed outwardly as at 23 to provide a recess for receiving the conical head when the button members are connected. 80

To permit of releasing the ends 22 of wire from the shank 18, there is formed eccentrically of the members 11 and 12 of the shell an axially aligned, circular opening 24, said opening being disposed to register 85 with the space between the ends 22 while the latter normally intersect the opening as is clearly illustrated in Fig. 1.

A suitable implement such as a stylus or 90 similar device having a tapered end is adapted to be inserted within the opening 24 to engage between the ends 22 of the wire and spread said ends sufficiently to disengage the same from the shank 18, after 95 which the button members may be readily detached as is apparent.

It will be noted that by providing the opening 15 in the top of the shell so that the stylus will extend transversely between the wire ends 22 excessive distortion of the latter such as might detract from the life of the button, will be prevented, the size of the opening 15 determining the degree to which said ends may be spread. 100

I am fully aware that separable fasteners embodying a somewhat similar detachable connection have heretofore been provided, but in these fasteners the stylus is inserted longitudinally between the yieldable portions of the connection, said portions being consequently distorted, and the life of the button materially shortened, there being no 110

provision for limiting the extent to which said portions may be spread. Furthermore an opening provided in the front face of the button is more accessible than one entering 5 from the side thereof and detachment of the elements of the button is in consequence facilitated.

What is claimed is:—

10 A separable fastener including head and back members said head comprising a shell provided with a central opening, and said back including a shank insertible through said opening, and spring fingers arranged

in said head and yieldably spaced apart to normally intersect the opening and detachably engage the shank, said head having therein an aperture opening at right angles to said fingers for the insertion of means transversely between the latter to spread and disengage the same from the shank. 15 20

In testimony whereof, I affix my signature, in the presence of two witnesses.

WILLIAM J. SMITH.
